Spencer Middleton Donaldson Hull
ATTORNEY.

UNITED STATES PATENT OFFICE.

ROBERT EDWIN REARDON, OF WASHINGTON, DISTRICT OF COLUMBIA.

TOY PISTOL.

Application filed March 2, 1921. Serial No. 449,219.

To all whom it may concern:

Be it known that I, ROBERT E. REARDON, a subject of the King of Great Britain, and a resident of Washington, in the District of Columbia, have invented certain new and useful Improvements in Toy Pistols, of which the following is a specification.

My present invention relates to improvements in toy pistols of the type designed to 10 explode paper caps and includes among its objects the following:

First, to provide a pistol which may be used by children with absolute safety;

Second, to provide a pistol of this type 15 which will be analogous to an automatic pistol;

Third, to provide a construction adapted for the utilization of paper caps in strip form; and

Fourth, to so construct the parts that the 20 pistol may be readily re-loaded when necessary.

With these and other objects in view, the 25 invention includes the novel features of construction and arrangement and combination of parts hereinafter described and particularly defined by the appended claims.

The preferred form of my invention is 30 illustrated in the accompanying drawings, in which:

Figure 1 is a side elevation of a pistol constructed to embody my invention.

Fig. 2 is a central longitudinal section.

Fig. 3 is a transverse section on line 3—3 35 of Fig. 1.

Fig. 4 is an end view.

Fig. 5 is a fragmentary longitudinal sectional view of a modification showing different positions of the hammer and trigger in 40 full and dotted lines.

Fig. 6 is an elevation of the form shown in Fig. 5 with the trigger guard dropped down.

Fig. 7 is a detail view.

Fig. 8 is a side view of a modification of 45 the means for preventing backward movement of the tape when the trigger member returns to normal position.

Fig. 9 represents a sectional view on the 50 line 9—9 of Fig. 8, the parts being shown in two positions, one clamping the tape, and one with the tape free.

Fig. 10 is a detail view of the clamp detached.

Referring by reference characters to these 55 drawings, the numeral 1 designates the pistol frame or casing as a whole, which includes the barrel 1^a, pistol grip 1^b and trigger guard 1^c, the whole being preferably shaped to conform in appearance to an approved type 60 of automatic pistol, the barrel portion being provided with sights as indicated at 2 and 3.

For convenience of manufacture and assembly, the said casing is preferably made in two sections or parts divided along the 65 longitudinal vertical line indicated at 1^d in Figs. 3 and 4, the parts being held together by screws 4, 4'.

Within the body of the casing is provided 70 an oscillating trigger member 5 having a finger grip portion 5^a which projects through an opening in the under side of the casing into the space enclosed by the trigger guard. This trigger member 5 is pivotally mounted 75 within the casing in any suitable manner and preferably upon the pivot pin 6, and it has an annular internal chamber 7, which is designed to receive a coil of paper caps in strip form, which is indicated at 8. The 80 said annular chamber of the trigger member which constitutes a magazine receptacle, is open at one side to permit the ready insertion and removal of the coil or roll, the re-loading being permitted by a movable side wall portion of closure 1^e operating in the manner 85 hereinafter more fully described.

The trigger member has a slot or opening indicated at *a* through which the end of the strip emerges from the coil holding chamber, from which opening the strip passes upward 90 initially underneath a weak tension spring around the curved exterior surface of the trigger member, which curved surface is indicated at *b*, and is designed to serve as an anvil portion or impact receiving part 95 to cooperate with the firing or exploding member which is preferably in the shape of a hammer 9.

The curved surface *b* is of approximately 100 semicircular form and terminates at its end remote from the slot *a* at an undercut shoulder *c* against which bears a leaf spring 10 preferably carried by the screw 4. It will be seen that the spring 10 lies in such 105 position that it forms a support for the used portion of the strip 7 as it passes from the anvil surface of the trigger and serves to guide such used portion into the bore of the

barrel from whence it may be removed by tearing off the projected portions from time to time.

The spring 10 above referred to serves to keep the finger grip portion 5^a pressed forward in the position shown in Fig. 2, the movement in this direction being limited by a portion *e* abutting against a shoulder 1^c of the frame or casing.

Carried by the trigger and overlying the strip exit slot is a friction grip member 11 which is designed to bear against the strip with sufficient friction to cause it to move with the trigger member in the rotation of the trigger and thereby feed the strip. The hammer member 9 is pivoted upon a pivot pin 12 located below the axis 6 of the trigger member and is provided with a hammer head designed to coat with the anvil surface of the trigger member above referred to. A spring 13 is provided to impart power to the hammer, which spring is preferably in the form of a leaf spring having a loop portion engaging the shank of the securing screw 4^a, one arm of the spring engaging a portion of the casing wall and the other arm bearing against a lug or projection 9^a of the hammer in rear of the pivot thereof.

The hammer is provided with a pivoted strut 14 which has an end positioned so as to abut against a rounded projection *f* on the trigger member near the extremity thereof as shown in Fig. 2. This strut is capable of a limited pivotal movement relative to the hammer and is pressed by spring action normally toward the trigger projection *f* to the limit of its movement in such direction. The preferred construction of strut is that shown in Fig. 2 in which the strut has one end bent into circular form as indicated at 14^a and inserted in a circular recess in the hammer, the shank of the strut extending through an opening at one side of said recess, which opening is of sufficient width to allow a certain amount of pivotal movement of the strut. The spring action of the strut referred to may conveniently be secured by a spring 15 having a loop portion lying within the eye of the strut and two arms extending outwardly and diverging and bearing respectively against the strut 14 and the face of the hammer.

Assuming the parts to be in the position shown in Fig. 2, a pull upon the finger grip portion 5^a will swing the latter rearwardly, and through the action of the projection *f* and strut 14 move the hammer back into the position shown in Fig. 5. Just at the limit of this movement, the free end of the strut will slip off of or snap past the end of the projection *f* which will free the hammer allowing it to be propelled by the spring 13 so as to strike and explode the cap supported by the anvil portion, whereafter the trigger will be free to be restored to normal position

by the action of its spring 10, the position of the parts during such movement being respectively as indicated in full and dotted lines in Fig. 5.

During the return movement of the trigger, the engagement of the hammer face with the strip will prevent backward movement of the strip with the hammer, the spring 11 sliding over the face of the strip. In other words, as the trigger swings back to initial position the strip remains stationary so as to bring a fresh cap to the firing point indicated by the star. The hammer face may be roughened if desired to assist the holding action. The feed step for any desired trigger travel may be varied by varying the radius of anvil periphery of the trigger member.

The closure 1^c provided for re-loading is preferably in the shape of a cover member which is hinged upon a pin 16. The shank of the pin is rigidly secured to the cover member and it is passed slidably through the wall of the casing, and has a head slidably fitting in an enlarged recess in said casing. A spring 17 encircling the pin within this recess normally forces the head 16^a to the left (Fig. 3) and holds the cover member in closed position. When it is desired to re-load the pistol, pressure upon the head or button 16^a will force the cover member outward until its edges clear the walls of the opening, at which time it may be swung downward to expose the roll chamber for a re-loading.

The cover member is provided with a shoulder *e'* which is designed to coat with the shoulder or portion *e* so that as the cover member is swung downwardly to expose the roll chamber the trigger will be simultaneously moved backward so as to cock the hammer and remove the hammer face from the surface of the strip so as to free the latter for removal.

In the modified form of loading means shown in Fig. 6, the trigger member and that portion of the side of the pistol on which it is mounted are released by pressing in the spring push button and pressing down on the trigger guard, thereby rotating the side of the pistol on its pivot until the cap magazine is exposed sufficiently to insert a roll of cap ribbon, while retaining the magazine edge portion under the cover-side of the pistol, this limited emergence allowing the trigger-magazine member to be mounted unrestrainedly on its pivot in assembling the pistol, thus simplifying manufacture.

In either form of my invention it will be seen that it is impossible to discharge the pistol while it is being reloaded. It will also be seen that as the caps can only be fired when the magazine is in place and the caps are completely enclosed, the pistol is absolutely safe.

Instead of depending upon the hammer 9 for holding the cap strip against retrograde movement while the trigger member 5 with its anvil is returning to normal position, I prefer to employ other means, consisting of a spring having a bent end or tooth portion 9^x to grip the cap tape at a point below that at which the face of the hammer strikes upon the said tape. This 10 renders the action more certain because some portion of the strip is liable to be blown away at the position of the hammer face, and therefore a full gripping effect of the hammer upon the strip at this point may not 15 take place, but with the spring grip 9^x located so as to act upon the strip at a point considerably below that at which the exploded part lies, certainty of action in the feeding of the strip will be the result, be- 20 cause as the trigger member with its mag-azine retracts to normal position, the point or tooth 9^x will retain the tape against back-ward movement with the trigger member, and thus a new length will be fed out by the 25 relative movement of the trigger member in respect to the projecting portion of the tape, so that when the trigger is again pressed, this newly fed portion will be carried for-ward to a position where it will be struck 30 by the hammer.

The grip 9^x may be provided in different ways but I prefer to provide it in the shape of a leaf spring having a cylindrical body portion 9' seated in an opening or socket in 35 the body of the hammer.

I have shown in Figs. 8 and 9 a modification of the gripping or clamping means for retaining the strip of caps against retrograde movement while the trigger member is 40 returning to normal position. This means consists of a clamp formed of two arms or members 16 and 17, these members being connected by the cross portion at 18, which is seated in the frame of the gun. The arm 45 16 of the clamp lies alongside of the anvil and the other arm is arranged opposite the hammer 9 and the tape passes between these two arms. The arm 17 of the clamp is pro-vided with a spring extension 17' to be borne 50 upon by a portion of the hammer, as shown in Fig. 8, and at the left of Fig. 9, so that the hammer in its striking position will close the clamp upon the tape and hold it against backward movement. This clamp is located 55 below the point where the explosion takes place. Its arm 17 is provided with a point 17^a and also a turned edge at 17^b which are adapted to engage the tape for holding it securely. The turned edge 17^b also serves as 60 a part of a shield of which the arm 17 forms the main part to protect the tape from being blown away by the explosion.

It will be noticed that when the clamp is closed, as shown at the left of Fig. 9 and 65 in Fig. 8, the tape is closely held between the

arms 16 and 17 of the clamp, and the turned edge 17^b, together with the two arms, pro-tects the tape from the effects of the explo-sion, so that certainty of feed of the tape will result from the movement of the trigger 70 member. It will be also observed that the tape at the point where it is clamped is not in contact with the anvil, but instead is held between the two arms of the clamp, so that the backward movement of the anvil 75 does not tend to move the tape backwardly, because it has no frictional contact there-with.

In Figs. 5 and 8 I show the strut 14 as having a straight extension 14^x on the strut 80 extending past the corner of the trigger member, while in the form shown in Fig. 2, the strut has a curved extension 14' which extends around a projecting portion of the trigger member, so as to act as a stop for 85 the return movement of the trigger member. This extension also insures the proper slip-ping off of the strut from the end 7 of the trigger member and keeps these parts in proper relative positions. 90

Having thus described my invention, what I claim is:

1. In a toy pistol, a movable trigger mem-ber having a magazine chamber for holding a supply of caps in strip form, and means 95 for feeding and exploding said caps.

2. In a toy pistol, a trigger member, a pivot pin supporting the same, said trigger having an annular chamber around said pivot pin for holding a roll of caps in strip 100 form, and means for feeding and exploding the caps.

3. In a toy pistol, a trigger member hav-ing a cap magazine and an anvil.

4. In a toy pistol, a trigger having a 105 magazine chamber for a supply of caps in strip form, and cap exploding means operable by said trigger, said pistol having a side wall movable to expose said magazine, and a transversely arranged push button 110 connected to directly operate said side wall.

5. In a toy pistol, a trigger having a mag-azine chamber for a supply of caps in strip form, and cap exploding means operable by 115 said trigger, said pistol having a side wall movable to expose said magazine, and means carried by said side wall for locking the ex-plosive means against action when the side wall is moved.

6. In a toy pistol, a trigger having a mag-azine chamber for a supply of caps in strip form, and cap exploding means operable by 120 said trigger, said pistol having a side wall movable to expose said magazine, said side wall having a projection coacting with the 125 trigger when said side wall is moved.

7. In a toy pistol, a casing, a trigger mem-ber carried thereby having a cap magazine chamber and cap exploding means, a spring 130 acting on said trigger, cap exploding means

associated with said elements, said trigger having a shoulder, and said casing a cooperating shoulder serving to limit the movement of the trigger, and said casing having a side wall movable to expose the magazine, and said wall having a shoulder also cooperating with the shoulder on the trigger.

8. A toy pistol having trigger member means therein for bodily moving a roll of caps in strip form to feed the same forward and means for exploding the caps.

9. In a toy pistol, a support for a roll of caps in strip form, trigger mechanism arranged to bodily rotate the roll to feed said strip step by step, and a hammer operated by said trigger.

10. In a toy pistol, an oscillating trigger, means for supporting a roll of caps in strip form and means whereby movement of the trigger in one direction bodily rotates the roll, feeds said strip and explodes a cap.

11. In a toy pistol, an oscillating magazine trigger member, having a hollow portion constituting a magazine for supporting a supply of caps in strip form, a cap exploding device and means whereby the movement of the trigger intermittently feeds the strip and explodes the caps.

12. In a toy pistol, an oscillating trigger member having an anvil surface and a recess for supporting a roll of caps in strip form, means whereby the movement of the trigger intermittently feeds said strip relative to said anvil surface, and a cap exploding device actuated by said trigger member.

13. In a toy pistol, a pivoted trigger member having an internal chamber to receive a coil of paper caps in strip form, said trigger member having an opening to permit the passage of the strip and an exterior anvil surface, means carried by the trigger for feeding the strip when the trigger is pulled, and a cap exploding device cooperating with said anvil portion and arranged to be cocked and fired by said trigger.

14. In a toy pistol, a pivoted trigger member having an internal chamber to receive a supply of paper caps in strip form, said trigger member having an opening for the passage of the strip and an exterior anvil surface over which the strip is guided, means carried by the trigger member for effecting frictional engagement of the strip to feed the same, and cap exploding means cooperating with said anvil surface and operated by said trigger.

15. In a toy pistol, a pivoted trigger member having an internal chamber to receive a supply of paper caps in strip form, said trigger member having an opening for the passage of the strip and an exterior anvil surface over which the strip is guided, means carried by the trigger member for effecting frictional engagement of the strip to feed

the same, and cap exploding means cooperating with said anvil surface and operated by said trigger, said exploding means being arranged to act on said strip to hold it stationary during return movement of the trigger.

16. In a toy pistol, a pivoted trigger member having a chamber to receive a supply of caps in strip form and an exit opening for the passage of the strip, a cap exploding means, means carried by the trigger for feeding the strip as the trigger is pulled, and means whereby the movement of the trigger actuates the exploding means.

17. In a toy pistol a pistol casing, a pivoted trigger having a chamber to receive a supply of paper caps in strip form, a spring pressed cap exploding device, means whereby the pulling of the trigger operates said firing device, and means whereby said movement of the trigger feeds the strip.

18. In a toy pistol a casing, a spring pressed trigger therein having a chamber to receive a supply of paper caps in strip form and an anvil part, a pivoted hammer, a spring normally pressing said hammer towards the anvil, means whereby the movement of the trigger feeds said strip, and means whereby the movement of the trigger first moves said hammer back against the pressure of its spring and then releases it.

19. In a toy pistol, the combination with the casing of a trigger pivoted therein having a chamber for a roll of caps in strip form, said trigger having a curved exterior anvil surface and an exit slot leading thereto, a spring acting on said trigger, a spring carried by the trigger and frictionally engaging the strip with the chamber, a spring pressed hammer cooperating with said anvil surface, and means whereby the movement of the trigger operates said hammer.

20. In a toy pistol, the combination with the casing of a trigger pivoted therein having a chamber for a roll of caps in strip form, said trigger having a curved exterior anvil surface and an exit slot leading thereto, a spring acting on said trigger, a spring carried by the trigger and frictionally engaging the strip with the chamber wall, a spring pressed hammer cooperating with said anvil surface, and means whereby the movement of the trigger operates said hammer, said casing having a side wall portion movable to expose said chamber for reloading.

21. In a toy pistol, the combination with the casing of a trigger pivoted therein having a chamber for a roll of caps in strip form, said trigger having a curved exterior anvil surface and an exit slot leading thereto, a spring acting on said trigger, a spring carried by the trigger and frictionally engaging the strip with the chamber wall, a spring pressed hammer cooperating with said anvil

surface, and means whereby the movement of the trigger operates said hammer, said casing having a side wall portion movable to expose said chamber for reloading and

5 lock the hammer.

22. In a toy pistol, the combination with the casing of a trigger pivoted therein having a chamber for a roll of caps in strip form, said trigger having a curved exterior 10 anvil surface and an exit slot leading thereto, a spring acting on said trigger, a spring carried by the trigger and frictionally engaging the strip with the chamber wall, a spring pressed hammer cooperating with 15 said anvil surface, and means whereby the movement of the trigger operates said hammer, said casing having a side wall portion movable to expose said chamber for reloading, and said movable side wall having 20 means for operating said trigger to retract and lock the hammer.

23. In a toy pistol, the combination with the casing having a barrel portion, of a trigger member pivoted in said casing and having 25 a chamber to receive a coil of paper caps in strip form, said trigger having a peripheral surface forming a bearing surface for the strip and an opening leading to such surface, means whereby the movement of the 30 trigger feeds said strip, a hammer pivoted in said casing arranged to be operated by the trigger, and a leaf spring arranged to act on said trigger, said leaf spring being positioned so as to direct the used strip from the 35 bearing surface of the strip into the barrel.

24. In combination in a toy pistol, a trigger member having a magazine chamber for a strip of caps and an anvil over which the 40 said strip is carried, a hammer to strike the caps upon the anvil, and means carried by the hammer for gripping the cap strip at a point below the hammer face for holding the 45 said strip against backward movement as the trigger member returns to normal position, substantially as described.

25. In combination in a toy pistol, a trigger member having a magazine chamber for a strip of caps and an anvil over which the 50 said strip is carried, a hammer to strike the caps upon the anvil, and means carried by the hammer for gripping the cap strip at a point below the hammer face for holding the 55 said strip against backward movement as the trigger member returns to normal position, said gripping means consisting of a spring member carried by the hammer, substantially as described.

26. In combination in a toy pistol, a trigger member having a magazine chamber for 60 a strip of caps and an anvil over which the said strip is carried, a hammer to strike the caps upon the anvil, and means for gripping the cap strip at a point below the hammer

face for holding the said strip against backward movement as the trigger member 65 returns to normal position, substantially as described.

27. In combination in a toy pistol, a trigger member having a magazine chamber for a strip of caps, and an anvil over which the 70 said strip is carried, a hammer to strike the caps upon the anvil, and clamping means for the cap strip acted upon by the hammer to hold said strip against retrograde movement with the trigger member, substantially as described. 75

28. In combination in a toy pistol, a trigger member having a magazine chamber for a strip of caps, and an anvil over which the 80 said strip is carried, a hammer to strike the caps upon the anvil, and clamping means for the cap strip acted upon by the hammer to hold said strip against retrograde movement with the trigger member, said clamping means consisting of two arms between 85 which the strip passes, said clamp holding the strip independent of contact with the anvil, substantially as described.

29. In combination in a toy pistol, a trigger member having a magazine chamber for a strip of caps, and an anvil over which the 90 said strip is carried, a hammer to strike the caps upon the anvil, and a clamp for holding the strip against backward movement consisting of two arms, one of which is arranged adjacent the surface of the anvil and the other in opposed relation thereto, and adapted to be pressed upon by the hammer, said arms receiving the strip between them, substantially as described. 95

30. In combination in a toy pistol, a trigger member having a magazine chamber for a strip of caps, and an anvil over which the 100 said strip is carried, a hammer to strike the caps upon the anvil, and a clamp for holding the strip against backward movement consisting of two arms, one of which is arranged adjacent the surface of the anvil and the other in opposed relation thereto, and adapted to be pressed upon by the hammer, said arms receiving the strip between them, said clamp being located below the point where the explosion takes place and having a turned edge to act as a shield for the tape against said explosion, substantially as described. 105 110

31. In combination in a toy pistol, a trigger member having an anvil, a hammer to strike the caps upon the anvil, a strut extending from the trigger member to the 120 hammer, said strut having a portion embracing the end of the trigger member to act as a stop for the return movement thereof, substantially as described.

In testimony whereof, I affix my signature. 125
ROBERT EDWIN REARDON.
